GAME DISPLAY PANEL

Frederick A. Hurley, 10911 NE. 10th Ave., Miami, Fla.

Filed Sept. 8, 1964, Ser. No. 81,629

Term of patent 14 years

(Cl. D34—5)

The figure is a perspective view of a game display panel, showing my new design.

The dominant features of my design reside in the portions shown in full lines.

I claim:

The ornamental design for a game display panel, as shown and described.
